UNITED STATES PATENT OFFICE.

LOUIS POSTAWKA, OF CAMBRIDGEPORT, MASSACHUSETTS.

IMPROVEMENT IN TABLES.

Specification forming part of Letters Patent No. **156,310**, dated October 27, 1874; application filed July 3, 1874.

CASE D.

To all whom it may concern:

Be it known that I, LOUIS POSTAWKA, of Cambridgeport, in the county of Middlesex and State of Massachusetts, have invented a new and Improved Table, of which the following is a specification:

The invention will first be fully described, and then pointed out in the claim.

Figure 1 is a sectional elevation of a table contrived according to my invention. Fig. 2 is a plan view with a part of the top broken out, and Fig. 3 is an enlarged section through one of the leg connections.

Similar letters of reference indicate corresponding parts.

A represents the table-top; B, the detachable frame fastened to the under side of the top. D represents a head-piece for connecting the legs to the table-top. E represents the legs, and F the connecting-bolts. The head-pieces are, in this example, long enough to extend across the table and serve for two legs. The legs are connected by a tenon, H, fitting in a socket, I, and the head-pieces are attached to the frame B by the bolts F, which extend through them from the sockets for the tenons, and pass up to the sockets G in the

upper side of the frame B for the nuts, by which they are screwed fast. The frame B is screwed onto the table-top in any approved way. The bolts F may, of course, be arranged out of the sockets; but in that case they would be exposed to view, or require special means for concealing them. The posts are mounted on foot-pieces J, which receive the two legs of each end, which, together with the head-pieces, form side frames, and the two frames are connected by a stretcher, K, screwing into them by right-and-left threads, to fasten them together detachably in a simple manner.

Having thus described my invention, I claim as new and desire to secure by Letters Patent—

The combination, with table-frame B, having recess above each leg, and the legs E having tenon H, of the bolts and nuts F G, and the intermediate blocks D having subjacent socket I, the said blocks being applied to table-frame and legs, all as and for the purpose described.

LOUIS POSTAWKA.
